UNITED STATES PATENT OFFICE.

JAMES HERMANN ROSENTHAL, OF LONDON, AND EDWIN CHARLES CARNT, OF EAST COWES, ISLE OF WIGHT, ENGLAND, ASSIGNEES TO BACCOCK & WILCOX, LIMITED, OF LONDON, ENGLAND, AND J. SAMUEL WHITE & COMPANY, LIMITED, OF EAST COWES, ISLE OF WIGHT, ENGLAND.

STEAM-GENERATOR.

1,167,841.

Specification of Letters Patent.

Patented Jan. 11, 1916.

Application filed July 20, 1911. Serial No. 639,477.

To all whom it may concern:

Be it known that we, JAMES HERMANN ROSENTHAL and EDWIN CHARLES CARNT, both subjects of the King of the United Kingdom of Great Britain and Ireland, and residing at London, England, and East Cowes, Isle of Wight, England, respectively, have invented a certain new and useful Improvement in Steam-Generators, of which

10 the following is a specification.

This invention relates to improvements in superheaters applicable to water-tube steam generators having a common overhead steam and water drum connected by banks of 15 tubes to separate water drums arranged on each side of the furnace below and parallel to the overhead drum.

More particularly the invention contemplates an improved arrangement of the 20 superheater in relation to the boiler tubes, and an improved arrangement of the tubes of the superheater in relation to the manifolds or boxes thereof, as hereinafter more fully described.

25 In the accompanying drawings Figure 1 is a longitudinal vertical section, Fig. 2 is a part elevation part vertical cross section, and Fig. 3 is a plan showing by way of example a steam generator of the type referred 30 to equipped with superheaters constructed and arranged in accordance with the invention; Figs. 4, 5 and 6 show details of the superheater.

It will be seen that each orifice in each 35 row is spaced from one of the two adjacent orifices in the same row a distance exceeding the diameter of a U-tube; that each U-tube is spaced from the water tubes forming the upper wall of the oval chamber 40 a distance exceeding the diameter of a U-tube and that the U-tube at each end of the chamber is spaced from the nearest drum a distance exceeding twice the radius of curvature of such U-tube, that is a distance 45 exceeding the distance between the two limbs of the U-tube. It will also be seen that by properly selecting the zone in which the superheater is placed, that is to say, disposing the surface of the fireside of the 50 superheater relative to the surface of the uptake side of the superheater as shown,

it is possible to maintain a constant degree of superheat at whatever rate the boiler is being worked.

The superheater shown comprises juxtaposed manifolds or boxes A and B one side of each of which is provided with orifices to receive the ends of U-shaped tubes C expanded thereinto, and the opposite side of each of which manifolds or boxes A and B 55 is provided with handholes D adapted to be closed by covers in a manner well understood. Some or all of the U-shaped tubes are arranged in pairs, the tubes of each pair being disposed in the same vertical plane 60 and all the tubes being parallel to the axes of the overhead drum E and bottom drums F; one U-tube of each pair being fitted within the space between the legs of the other U-tube of that pair, so that the orifice into 65 which the four upper ends or the four lower ends of two adjacent pairs of tubes are expanded are accessible through one handhole on the opposite side of the corresponding box. 75

In order to accommodate the superheaters, each of the banks of boiler tubes G (or, if a single superheater be used, one of the banks) is subdivided into two sub-banks or semi-banks, the tubes of the two sub-banks being 80 oppositely curved, that is, curved concavely relatively to each other, so as to afford between them a chamber H of substantially oval formation in cross section, the major axis of which lies in a plane considerably 85 inclined to the vertical.

As shown, the superheater boxes are inclined to correspond with the inclination of the major axis of the oval chamber, and as 90 the tubes fitted within said chamber lie in approximately vertical planes, it will be understood that an extensive staggering of the tube hole is provided and a considerable distance afforded between the holes for receiving the two ends of each U-tube, so as to provide for a large radius of curvature at the bend of the U-tube. 95

As shown, valved pipe connections I and J are interposed between the overhead drum E and the superheater on the one hand, and between the superheater and the main steam supply pipe on the other hand. 100

Having now described our invention what we claim and desire to secure by Letters Patent of the United States is:—

1. A steam generator, comprising a combustion chamber, an offtake for the gases, a steam and water drum, a mud drum below the steam and water drum and at one side thereof, a plurality of sets of inclined water tubes within the combustion chamber and in the direct path of the gases to the offtake flue and connecting the steam and water drum to the mud drum, headers at one end of the generator, U-shaped superheater tubes connected to said headers, both legs of said tubes extending in a longitudinal direction between the sets of water tubes and at approximately right angles to the water tubes, the arrangement being such that the gases in passing from the combustion chamber to the offtake flue will pass transversely over one set of water tubes, the superheater tubes, and then the second set of water tubes without changing the general course of the gases; substantially as described.
2. A steam generator, comprising a combustion chamber, an offtake flue for the gases, a steam and water drum, a plurality of mud drums below the steam and water drum, there being one of said mud drums at each side of the steam and water drum, a plurality of sets of water tubes connecting each mud drum with the steam and water drum within the combustion chamber and in the direct path of the gases to the offtake flue, headers at one end of the generators, and U-shaped superheater tubes connected to said headers the legs of said tubes extending in a longitudinal direction between the sets of water tubes and at approximately right angles to the water tubes on the opposite sides of the respective spaces, the arrangement being such that the gases in passing from the combustion chamber to the offtake flue will pass approximately over the water tubes and the superheater tubes without changing the general course of the gases; substantially as described.
3. A steam generator, comprising a steam and water drum, a mud drum below the steam and water drum and at one side thereof, a plurality of sets of inclined water tubes within the combustion chamber and in the direct path of the gases of the offtake flue connecting the steam and water drum to the mud drum, headers at one end of the generator, and U-shaped superheater tubes connected to said headers, both legs of said tubes extending in a longitudinal direction between the sets of water tubes and at approximately right angles to the water tubes, the upper legs of the intermediate tubes being approximately central between both legs of an adjacent tube, while the lower legs of the intermediate tubes are approximately centrally located between the legs of an adjacent tube at the other side, the arrangement being such that the passage for the gases transversely across the superheater tubes will not be restricted in a plane extending through the upper and lower legs of the superheater tubes; substantially as described.
4. A steam boiler, having a single combustion chamber extending from one side of the setting to the other, a central steam and water drum, two mud drums below the steam and water drum, there being one mud drum on each side of the combustion chamber, two banks of inclined tubes one on each side of the setting bent to substantially the same radius within the combustion chamber and in the direct path of the gases to the offtake and connecting the steam and water drum with the mud drums, each bank being divided into two groups so as to form between them an oval chamber having an inclined major axis, a superheater in each chamber between the groups comprising parallel and contiguous header boxes in approximately the same plane as the major axis of the chamber, and U-tubes connecting these header boxes extending transversely across the banks of water tubes within the oval chamber, one end of each U-tube being connected to one header box and the other end to the other header box; substantially as described.
5. A steam boiler, having a single combustion chamber extending from one side of the setting to the other, a central steam and water drum, two mud drums below the steam and water drum, there being one mud drum on each side of the combustion chamber, two banks of inclined tubes one on each side of the setting bent to substantially the same radius within the combustion chamber and in the direct path of the gases to the offtake flue and connecting the steam and water drum with the mud drums, each bank being divided into two groups so as to form between them an oval chamber having an inclined major axis, a superheater in each chamber between the groups comprising parallel and contiguous header boxes in approximately the same plane as the major axis of the chamber, and U-tubes connecting these header boxes extending transversely across the banks of water tubes within the oval chamber, one end of each U-tube being connected to one header box and the other end to the other header box, the upper header being divided into two parts, the steam entering one of the compartments of the upper box and then passing through the U-tubes to the other header, and from the last mentioned header to the steam offtake through the other compartment of the first mentioned header; substantially as described.
6. A steam boiler, having a single combustion chamber extending from one side of the setting to the other, a central steam and water drum, two mud drums below the steam and water drum, there being one mud drum on each side of the combustion chamber, two banks of inclined tubes one on each side of the setting bent to substantially the same radius within the combustion chamber and in the direct path of the gases to the offtake flue and connecting the steam and water drum with the mud drums, each bank being divided into two groups so as to form between them an oval chamber having an inclined major axis, a superheater in each chamber between the groups comprising parallel and contiguous header boxes in approximately the same plane as the major axis of the chamber, and U-tubes connecting these header boxes extending transversely across the banks of water tubes within the oval chamber, one end of each U-tube being connected to one header box and the other end to the other header box; substantially as described.

- tion chamber extending from one side of the setting to the other, a central steam and water drum, two mud drums below the steam and water drum, there being one mud drum on each side of the combustion chamber, two banks of inclined tubes one on each side of the setting bent to substantially the same radius within the combustion chamber and in the direct path of the gases to the 10 offtake flue and connecting the steam and water drum with the mud drums, each bank being divided into two groups so as to form between them an oval chamber having an inclined major axis, a superheater in each 15 chamber between the groups comprising parallel and contiguous header boxes in approximately the same plane as the major axis of the chamber, and U-tubes connecting these header boxes extending transversely across the banks of water tubes 20 within the oval chamber, one end of each U-tube being connected to one header box and the other end to the other header box, the upper header being divided into two parts, the steam entering one of the compartments of the upper box and then passing through the U-tubes to the other header, and from the last mentioned header to the steam offtake through the other compartment of the first mentioned header, the arrangement being such that the entering steam flows in parallel through half of the U-tubes while the steam leaving the superheater flows in parallel through the other half of the U-tubes; substantially as described. 25 30 35

In testimony whereof we have signed our names to this specification in the presence of two subscribing witnesses.
